CLAIM

The ornamental design for the a combined biopsy stylet and biopsy cannula, as shown and described.

DESCRIPTION

FIG. 1 is a side elevational view of a combined biopsy stylet and biopsy cannula showing our new design, the center of the needle is shown broken to indicate indeterminate length; FIG. 2 is an enlarged side elevational view thereof, the opposite side elevational view being identical thereto. The tip of the needle is shown removed for ease of illustration; FIG. 3 is a top plan view thereof; FIG. 4 is a bottom plan view thereof; FIG. 5 is an end elevational view thereof; FIG. 6 is a cross-sectional view thereof, taken along the line 6—6 of FIG. 2; FIG. 7 is a cross-sectional view thereof, taken along the line 7—7 of FIG. 2; FIG. 8 is a cross-sectional view thereof, taken along the line 8—8 of FIG. 2; and, FIG. 9 is a cross-sectional view thereof, taken along the line 9—9 of FIG. 2.
